UNITED STATES PATENT OFFICE.

HERMANN HEINRICH KÖNEMANN, OF MUNSTER, GERMANY.

VACUUM TUBE.

Application filed September 4, 1923, Serial No. 680,814, and in Germany September 8, 1922.

My invention refers to vacuum tubes or mercury vapor rectifiers and its particular object is an improvement upon the tubes or rectifiers hitherto used which allows of using 5 such a tube as a high current relay for varying direct or alternating current, so as to obtain a predetermined characteristic.

Up till now, one has not succeeded in transferring the principle underlying the 10 electron tube of controlling an electron flow by means of a grid potential upon the control and regulation of high currents. Moreover, it has especially proved impossible to produce high current with the aid of free 15 electrons.

According to my invention, this problem is solved by employing the conductive path 20 created by the ions of a mercury arc. Although it is possible to influence the conductivity of a flow of ions by a grid, this is much more difficult, from the physical stand-point, than to influence a pure flow of electrons. Moreover, the grid becomes heated in 25 the path of the current and consequently ionizes the mercury vapors surrounding it, so that the whole behaves like an electron tube with a comparatively high content of gas.

According to the present invention, I overcome these difficulties by employing as 30 controlling member a body capable of being kept cool. In practising my invention, I can for instance introduce into the current traversing the mercury rectifier a coiled iron tube adapted to be supplied with a cooling liquid, 35 this tube being disposed in such a manner that the current is forced to pass through between the coils.

It has now been ascertained that with an 40 arrangement such as described above, when the device is not working, little drops of mercury will settle on the cooling tube by condensation, and, if subsequently the tube is again supplied with current, these drops of mercury will cause disturbances. It is, 45 therefore, necessary to prevent such precipitation of mercury from arising. This can be effected by supplying the cooling tube instead of with a cooling liquid, with a current of hot air serving to maintain the temperature of this controlling member at a point 50 lying between the temperature at which the tube is heated to red heat and the temperature of condensation of mercury.

In the drawings affixed to this specifica-

tion and forming part thereof several embodiments of my invention are illustrated diagrammatically by way of example.

In the drawings—

Figure 1 is a diagram of a rectifier tube embodying my invention, and

Figure 2 is a system comprising a tube of the kind aforesaid in combination with means for regulating it.

Figures 3-14 are diagrams illustrating different characteristics of the current.

Referring first to Figure 1, G is a vacuum tube or vessel and Q is the negative mercury electrode, while Z is the ignition electrode which serves for permanently heating part 70 of the surface of the mercury. A is the main electrode. If a corresponding voltage is supplied to A, there results a current between A and Q which is forced to pass through between the windings of a corresponding tube S disposed intermediate the electrodes and extending across the tube G. The distance between the windings of the coil S is chosen corresponding to the particular conditions 75 of the current, while in all other respects the shape and configuration of the coil S may be varied at will.

Experience has further shown that with a controlled mercury arc rectifier as described above, large currents can be thrown in and out, provided that they traverse the rectifier 80 in the form of alternating current, and more especially in the form of semi-periods of such current. On the other hand, the control of direct current at higher intensities 85 has proved to be practically impossible. In order now to be able to control also direct current, I cause it to be interrupted periodically by means of an oscillation circuit which is connected in parallel to the mercury arc and the elements of which, and more especially 90 the capacity, are so chosen that the amplitude of the alternating current is greater than the amplitude of the direct current. If, now, the cooling grid is kept negative with regard to the anode in such manner that all 95 lines of force emanating from the anode end of the grid, no current can pass through, the formation of a current being possible only on the grid potential being varied in such manner that the lines of force can pass through it. It is thus possible, by merely 100 controlling the potential of the grid, to predetermine whether and when the current 105

shall again be formed. The same applies also to each individual oscillation period of the circuit connected in parallel.

In consequence thereof, it is possible by adjusting the voltage to cause the current to be started sooner or later, in other words, to vary the time during which the current shall flow within the single periods. When this current has once been started, it does not heed the grid, but continues flowing until the oscillation circuit interrupts it again. The regulation is, therefore, effected in such manner that the single current impulses act during periods of different lengths. By the compensating inductivities or capacities the effects of the individual impulses are then caused to be adapted to the form of the voltage curve to be amplified, for instance the current curve of the microphone. This latter way of proceeding can therefore be characterized in such way that direct current is subdivided in a mercury arc rectifier by aid of an oscillation circuit into individual main current impulses which are then regulated by imparting to the grid at the different moments a voltage which causes the current to be started sooner or later within the oscillation periods of the circuits, the duration of which is the same, in accordance with the predetermined voltage.

In consequence thereof, I may for instance employ the arrangement shown diagrammatically in Figure 2, where G is the vacuum vessel, while A is the anode, Q the mercury cathode, H the heating electrode, L—C the oscillation circuit interrupting the current and influencing the potential of the grid S by aid of T_2 . A system of this kind operates as follows:—The alternating current i_a (Fig. 3) to be amplified accordingly impresses its voltage for the time being by aid of T_1 (Fig. 2) onto the controlling grid S. According, now, as the controlling potential influenced by T_1 and T_2 allows the lines of force to pass from the anode to the cathode or prevents them from doing so, the current will be started at each oscillation sooner or later or not at all. As soon, however, as it has acquired a certain value, it becomes independent of the control by the grid and would then continue flowing, unless interrupted by the oscillation circuit L—C. The elements of these circuits, and more particularly the capacity are adapted to the output of the relay and are so chosen that the energy oscillating in the circuit suffices to interrupt the direct current with certainty. e_c (Fig. 4) illustrates the variations of voltage at the condenser C, while i_v (Fig. 5) represents the direct current impulses formed, the effect of which is brought by compensating inductances or capacities to the form of the curve i_v (Fig. 6) which represents an amplification of i_a . The dimensions of the compensating elements men-

tioned above should again be adapted to the output of the relay and quite especially to the period of the oscillation circuit, in order to obtain a non-distorted image of the controlling voltage in the direct current circuit. 70

If instead of T_1 an optional or positively controlled variation of the voltage is inserted, the system described not only allows to throw in and out direct current, but also to regulate it at will. This involves the advantages that this regulation takes place absolutely free of the effects of inertia and does not require any resistances inserted in the circuit. 75

Instead of the back coupling between the grid and the oscillation circuit as shown in Fig. 2, I may as well employ a foreign control of the grid, provided that care be taken to cause the oscillation circuit and the grid potential to be in phase. 80

The curve i_v (Fig. 6) shows that there exists a direct current component, the magnitude of which can be determined in the following way:—If the curve i_1 in Fig. 8 represents the current impulses created by the direct current during the first semi-period of an oscillation of the circuit and if e_{st} (Fig. 7) represents the potential of the grid which must be obtained before the current can be started; if further e_m (Fig. 7) is the medium position of the grid potential e_g , about which it varies during the single oscillations, then as long as the grid potential is below e_{st} no current can pass through. As soon, however, as it reaches the line e_{st} , the current is started and will now continue until the end of the first semi-period. The least passage of current obtainable, apart from the case of total interruption, would be obtained in the case where the line e_m descends so far that the point of e_g just touches the line e_{st} (Fig. 9). In this case only the two halves of the first semi-periods will pass through which, being modified by the inductances and capacities, result in a direct current component. It is impossible to go still farther down, so that with regard to the separation of direct and alternating current, the curve shown in Fig. 6 is obtained. 100

Further essential advantages are obtained if the first point of intersection (Fig. 7) or the point of contact (Fig. 9) between e_g and e_{st} is shifted farther to the right (Fig. 11), the time during which the current is allowed to act being thereby further shortened. This can be accomplished technically by giving to the curve e_g a distorted form, such as is obtained if a sinusoidal current is caused to pass through an induction coil, the iron core of which is more or less saturated magnetically. For this purpose there is inserted in the line leading to the grid a choking coil T_3 , the iron core of which is more or less saturated by the direct current which passes from the battery B over the variable resist- 115

ance W . According to whether more or less resistance is inserted in the said line, the core will be more or less saturated and according to the degree of saturation the curve e_g will be more or less distorted. It is thus possible to shift the point of intersection from e_g (now called e_g^x) with e_{st} further to the right, so that it now intersects the line e_{st} in the second half of the first semi-period, 10 and in the case of maximum saturation, just before the end of the said semi-period, as is shown in the hatched portion of Figure 12. As it is possible to vary at will the direct current line by modifying the resistance W 15 (Figure 14), thereby varying also the degree of saturation of the iron core of T_3 , it is thus likewise possible to vary at will the current through the vacuum vessel, that is to zero. In this modification no direct current 20 component is formed. The current impulses are illustrated in Fig. 13. It is not essential that the changes of the current should be produced in the choking coil as shown, namely by changes of the resistance W (Fig. 25 14). For the same purpose any arrangement enabling the intensity of the magnetizing current to the modified may be used. Accordingly a microphone may be inserted in place of the resistance W . I wish it to be understood that I do not desire to be limited to the exact details of 30 construction, nor to the exact arrangement of parts shown and described, for obvious modifications will occur to a person skilled 35 in the art.

I claim:—

1. The method of operating a mercury vapour tube comprising forming in said tube a mercury vapour arc and maintaining a current of hot air in the path of said arc. 40
2. The method of operating a mercury vapour tube comprising forming in said tube a mercury vapour arc, maintaining a current of hot air in the path of said arc and peri-

odically in constant succession interrupting 45 the current forming said arc.

3. A vacuum tube comprising a pair of electrodes, means for striking a mercury vapor arc between said electrodes, means for maintaining a current of hot air in the path 50 of said arc and an oscillation circuit for periodically interrupting the current forming said arc.

4. A vacuum tube comprising a pair of electrodes, means for striking a mercury vapor arc between said electrodes, means for maintaining a current of hot air in the path 55 of said arc, an oscillation circuit for periodically interrupting the current forming said arc and means for varying the potential 60 of said air current maintaining means so as to permanently throw the current in and out.

5. A vacuum tube comprising a pair of electrodes, means for striking a mercury vapor arc between said electrodes, a tubular grid in the path of said arc, means for feeding said grid with hot air, an oscillation circuit, means for causing said circuit to periodically interrupt the current forming said 65 70 arc and means for causing said grid to control the passage of said current.

6. The method of operating a mercury vapour tube comprising forming a mercury vapour arc between the electrodes in said tube 75 and causing a current of hot air to pass through one of said electrodes.

7. Vacuum tube comprising a pair of electrodes, a grid intermediate said electrodes, means for striking a mercury arc between 80 said electrodes, an inductance, a partly magnetically saturated iron core in said inductance, and means for sending the sinusoidal current charging said grid through said inductance. 85

In testimony whereof I affix my signature.
